UNITED STATES PATENT OFFICE.

DAVID W. ROWLANDS, OF MINERSVILLE, PENNSYLVANIA.

DRILL.

No. 909,124.

Specification of Letters Patent.

Patented Jan. 5, 1909.

Application filed April 17, 1908. Serial No. 427,714.

To all whom it may concern:

Be it known that I, DAVID W. ROWLANDS, a citizen of the United States, residing at Minersville, in the county of Schuylkill and State of Pennsylvania, have invented new and useful Improvements in Drills, of which the following is a specification.

This invention relates to improvements in drills such as are employed for coal or other mining; one object of the invention being to effect an improvement in the construction of the drill bits; another object being to improve the construction of the socket member to which the drill bits are attached; a further object being to combine with the socket member a revoluble locking member having wedge-shaped fingers to engage the shanks of the bits and detachably lock the bits to the socket member.

With these and other objects in view the invention resides in the novel construction of elements and their arrangement in operative combination hereinafter fully described and claimed.

In the accompanying drawings, Figure 1 is a side elevation of a drill constructed in accordance with this invention. Fig. 2 is a central longitudinal sectional view of the same. Fig. 3 is a transverse section upon the line 3—3 of Fig. 1 on an enlarged scale. Fig. 4 is a side elevation of the locking member. Fig. 5 is a perspective view illustrating different forms of chisel bits employed with the present invention.

In the accompanying drawings the numeral 1 designates the main stock of the drill. This stock 1 comprises a plurality of tubular members having their ends provided with male and female threads whereby a number of members may be successively coupled together to enlarge the stock of the drill when desired. The hollow members 1 are provided with longitudinally extending transverse alining slots or openings 2, the purpose of which will hereinafter be set forth. The upper member of the stock 1 is adapted for the reception of a tamping element 3. This tamping element or member is constructed of copper and is provided with a longitudinal slot 4, adapted to provide a means for the insertion of a needle while the powder is tamped in the hole made by the drill.

The lowermost member of the main stock 1 is provided with a reducing coupling 5. This coupling 5 is provided with a central bore 6, and a reduced threaded collar 7 hav-

ing exterior threads adapted to engage with the interior threads of the lower member of the main stock, and whereby the two elements are connected. The coupling member 5 is also provided with an interiorly threaded portion 8, adapted for the reception of a threaded extension 9 provided upon a socket member 10. This coupling member 10 is provided with a central opening 11 alining with the opening 6 of the coupling 5 and the bores of the members of the main stock 1. The socket 10 is provided with a series of spaced vertical bores or channels 12, positioned adjacent the perimeter of the socket. These bores 12 are adapted for the reception of a reduced shank 13 provided upon the bits 14. The shanks 13 are provided with transverse slots or cut away portions 15, and these cut away portions are adapted to be engaged by the tapering fingers 16 provided upon a locking member 17 positioned upon the thimble 9 of the coupling 10 between the body of the coupling and the member 5.

By reference to Fig. 3 of the drawings it will be noted that the fingers 16 of the member 17 are spaced equidistant apart so as to provide an intermediate space between the fingers whereby the shanks 13 of the bits 14 may be positioned within the bore 12 of the socket 10 and the slot 15 brought into position to be engaged by the wedge shaped fingers 16 when the locking member 17 is rotated to securely retain the bits upon the socket.

The bits 14, it will be noted by reference to Fig. 5 of the drawings, may be constructed in any variety of shapes, but each is provided with an upper rectangular portion 18, and the lower base of the socket 10 is also provided with a plurality of rectangular openings radiating from the center and communicating with the bores 12 and adapted for the reception of the rectangular portions 18 of the bits.

In arranging the bits upon the socket a plurality of chisel bits 19 are positioned centrally of a plurality of side cutting bits 20. The side bits are sharpened at an angle to the center bits, and it will be noted that by this arrangement the drill presents a plurality of cutting surfaces arranged at angles to each other whereby the boring or churning of the material is rendered comparatively easy.

By reference to Fig. 2 of the drawings it will be noted that the inner edges of the bits

are spaced a slight distance away from each other so as to provide a passage communicating with the central bore of the device, thus providing means whereby the material in 5 which the drill is worked is forced through the bore and out through the longitudinal openings 2, thus providing means whereby the formation of the substance is readily determined and whereby the bore is effect- 10 ively cleaned.

Having thus fully described the invention what is claimed as new is:

1. In a drill, a main stock, a socket member connecting with the main stock, a locking 15 member upon the socket member provided with spaced wedge shaped fingers, the socket member being provided with a plurality of longitudinal bores, chisel bits having reduced shanks provided with transverse channels 20 for the bores of the socket member, and the transverse channels of the shanks adapted to be engaged by the wedge shaped fingers of the locking member.
2. In a drill, a main shank having a cen- 25 tral bore, a coupling also provided with a central bore and having a threaded exten-

sion connected with the main shank, a socket member having a reduced extension and provided with a central bore connected with the coupling, the socket member being provided with a plurality of spaced longitudinal openings adjacent its perimeter and having radiating passages at its lower face communicating with the openings, a locking member rotatably mounted upon the extension of the 30 socket member and provided with wedge shaped fingers, chisel bits having their body portions provided with reduced shanks having transverse slots, for the bores of the socket member, and the transverse slots of 40 the shanks adapted to be engaged by the wedge shaped fingers of the locking member to position the bodies of the bits within the radiating passages provided upon the face of the socket member. 45

In testimony whereof I affix my signature in presence of two witnesses.

DAVID W. ROWLANDS.
